UNITED STATES PATENT OFFICE.

ALONZO GRIGGS, OF WHITE STORE, NORTH CAROLINA.

CHURN.

No. 923,644.

Specification of Letters Patent.

Patented June 1, 1909.

Application filed October 7, 1908. Serial No. 456,575.

To all whom it may concern:

Be it known that I, ALONZO GRIGGS, a citizen of the United States, residing at White Store, in the county of Anson and State of North Carolina, have invented new and useful Improvements in Churns, of which the following is a specification.

This invention relates to churns, and particularly to mechanism for operating churn dashers of the reciprocating type, the object of the invention being to provide a simple, efficient and easily actuated type of operating mechanism in which the parts are combined and arranged in a novel manner to secure simplicity of structure with maximum strength and durability.

The invention consists of the features of construction, combination and arrangement of parts hereinafter fully described and claimed, reference being had to the accompanying drawing, in which:—

Figure 1 is a vertical transverse section taken on the line 1—1 of Fig. 2. Fig. 2 is a vertical front to rear section taken on the line 2—2 of Fig. 1. Fig. 3 is a horizontal section taken on the line 3—3 of Fig. 2. Fig. 4 is a rear elevation of the upper part of the frame and the gearing, a part of the fly wheel being broken away to better show the construction.

The frame work of the churn comprises four uprights or corner posts 1, a bottom platform 2, and suitable bars connecting the corner posts at their upper ends, as herein-after described. The corner portions of the base of the frame are provided below the platform with wheels or rollers 3, by which the apparatus may be conveniently transported from place to place. The churn body or receptacle 4 is adapted to rest upon the platform and to fit at its lower end within a suitable annular retainer 5, by which it is held in position.

The posts 1 at each side of the frame are connected by upper and lower side bars 6 and 7 and intermediate side bars 8, and the corner posts at each side are connected at front and rear by cross bars 9 and 10 disposed in the same plane as the intermediate cross bars 8. The bars 6 are connected in turn by a cross bar 11, the bars 7 by a cross bar 12, arranged in alignment with said bar 11, and the bars 8 by a cross bar 13 arranged in rear of the vertical plane of the bars 11 and 12, forming a simple, strong and durable frame structure at the top which is adapted to sup-

port the operating parts in a simple and effective manner.

The churn dasher 14 is mounted to reciprocate vertically in an opening 15 in the churn receptacle and the upper free end of its rod 16 is adapted to fit within the lower end of a sleeve or collar 17 mounted upon the lower end of a vertically reciprocating rod 18, said collar or sleeve being provided with a set 60 screw 19 to detachably couple the rod 16 thereto, whereby the dasher may be readily and conveniently connected with and disconnected from the operating mechanism.

The operating rod 18 is mounted to slide 70 in bearings 20 on the rear faces of the cross bars 11 and 12 and carries a longitudinally slotted transverse bar 21, the slot in which bar receives a crank pin 22 on the front face of a disk 23, whereby when said disk 75 is rotated continuously in one direction the pin will travel in the slot of the bar 21 and vertically reciprocate the rod 18 which will transmit corresponding motion to the dasher.

The disk 23 is mounted upon the forward end of a countershaft 24 journaled in bearings 25 on the cross bars 10 and 13. On the outer or rear end of this shaft is mounted a fly or balance wheel 26 and a pinion 27. 85 The pinion 27 meshes with a transmitting gear 28 mounted on a stub shaft journaled in a bearing 29 on the bar 10, and the gear 28 in turn meshes with a gear or pinion 30 on a drive shaft 31. The shaft 31 extends 90 at one side of the center of the frame from front to rear thereof and is journaled in bearings 32 on the bars 9 and 10 and provided at its forward end with a crank handle 33 or any other suitable type of operating 95 device. By this construction the shaft 31 may be driven and will in turn communicate motion through the train of gearing described to the countershaft 24, a uniformity of motion being maintained by the fly 100 wheel, and the countershaft will in turn drive the disk 23, the crank pin 22 of which will operate in the slot of the bar 21 and impart a vertical reciprocating movement to the operating rod 18 and dasher 14, as will 105 be readily understood.

It will of course be understood that in the operation of churning, the milk or cream is placed in the receptacle 4, the cover and dasher applied, the dasher rod coupled to 110 the operating rod 18, and the operating mechanism then set into action. At the end

of the churning operation the dasher is disconnected from the operating rod, leaving the same and the receptacle free for removal to complete the process of gathering the 5 butter, etc. The wheels or rollers 3 adapt the apparatus to be conveniently rolled from place to place, as circumstances require, thus adding to the convenience of the mechanism.

It will be observed that the construction 10 of the upper part of the frame is such as to provide for the firm fastening of all of the elements thereof together, and for the secure mounting of the parts of the gearing, without complicating the structure, the arrangement 15 of the cross bars forming the supports for the elements of the gearing also serving to transmit the strain so that it will be equally sustained by all of them, thus enabling the apparatus to be constructed at a comparatively 20 small cost.

Having thus fully described the invention, what is claimed as new is:

A churn comprising a rectangular frame embodying corner posts, a supporting platform connected with the lower ends of the corner posts, upper, lower and intermediate side bars connecting the upper ends of the posts at each side of the frame, front and rear cross bars connecting the posts at front

and rear of the frame, said cross bars being arranged in the horizontal plane of the intermediate side bars, upper and lower cross bars connecting the upper and lower side bars and provided with bearings, an intermediate cross bar arranged in rear of the 35 plane of said upper and lower cross bars and connecting the intermediate side bars and provided with a bearing, an operating rod mounted to reciprocate vertically in the bearings on the upper and lower cross bars, 40 a counter-shaft journaled in bearings on the intermediate and rear cross bars, an operative connection between said rod and counter-shaft, a pinion upon said counter-shaft, a transmitting gear journaled on the rear cross 45 bar and meshing with said pinion, a drive shaft extending from front to rear at one side of the frame, and journaled in bearings on the front and rear cross bars and provided at its rear end with a gear meshing with said 50 transmitting gear, and a power applying device connected with the front end of the shaft.

In testimony whereof I affix my signature in presence of two witnesses.

ALONZO GRIGGS.
